UNITED STATES PATENT OFFICE.

WILLIAM J. DODGE, OF SAN DIEGO, CALIFORNIA.

GAS TURBINE-ENGINE.

1,353,733.

Specification of Letters Patent. Patented Sept. 21, 1920.

Application filed June 13, 1919. Serial No. 303,909.

To all whom it may concern:

Be it known that I, WILLIAM J. DODGE, a citizen of the United States, residing at San Diego, in the county of San Diego and

5 State of California, have invented new and useful Improvements in Gas Turbine-Engines, of which the following is a specification.

This invention relates to internal combustion engines of the rotary turbine type, the 10 object in view being to produce an engine of light weight, economical to manufacture embodying in connection with a rotor and stator, an annular series of stationary cylinders 15 surrounding said rotor and stator, each of said cylinders comprising a combustion chamber and a piston, together with means for admitting explosive mixture to said cylinders and igniting the same therein, the 20 expanding mixture being then delivered to the vanes of the turbine section of the engine in a manner to produce the best results.

A further object of the invention is to 25 provide in conjunction with the arrangement above referred to, means for locking the pistons of said cylinders against movement, together with governor controlled means for unlocking and releasing said pistons prior to the ignition of the compressed 30 charges of mixture in the cylinders, whereby the power of the engine may be automatically controlled to suit variations in the load imposed thereon, also enabling a predetermined speed of the engine shaft to be maintained under varying loads.

35 With the above and other objects in view, the invention consists in the novel construction, combination and arrangement of parts, herein fully described, illustrated and 40 claimed.

In the accompanying drawings:—

Figure 1 is a vertical sectional view of the 45 complete engine, said view being taken about in line with the central vertical rotor shaft. Fig. 2 is a horizontal section through the same in a plane which intersects the vanes of the turbine part of the engine.

Fig. 3 is a top plan view of the engine, certain parts of the governor mechanism 50 being shown in section.

Fig. 4 is an enlarged vertical section taken about in line with the rotor shaft, illustrating a part of the governor control mechanism for actuating the tappets.

55 Fig. 5 is a vertical sectional view of one

of the cylinders, showing also one of the fuel and air intake valves used in conjunction therewith.

Fig. 6 is a plan view of the same.

Fig. 7 is a fragmentary vertical transverse 60 section through a cylinder head, showing the piston locking dogs and the means for operating the same and also operating the stem of the respective air and fuel intake valve.

Fig. 8 is a fragmentary plan view of the same, showing the coöperation of the locking dogs.

Fig. 9 is a detail perspective view showing one of the push rods, and parts immediately adjacent thereto.

Fig. 10 is an enlarged vertical sectional view of one of the fuel and air intake valves.

The engine contemplated in this invention comprises a supporting base 1 from which 75 rises a vertical wall or support 2 having a flange 3 at the top thereof upon which is mounted an annular support or multiple cylinder head 4. Superimposed upon the multiple cylinder head or annular support 4 80 is a second series of cylinders 5 each of which is closed at its upper end by a head 6 having a centrally arranged stuffing box 7 through which is slidably a check or stop rod 8 forming the piston rod of a piston 9 85 mounted to move up and down in the respective cylinder 5. The space between the piston 9 and the bottom head or support 4 forms a combustion chamber 10, while a compressed air chamber 11 is formed between said piston and the upper head 6 of 90 the cylinder. A spark plug 12 is inserted through the center of the cylinder at the bottom thereof to ignite the compressed mixture in the combustion chamber 10. In 95 the upper head 6 there is arranged an automatic air inlet valve 13 and the air compressed in the chamber 12 is forced past a check valve 14 through an outlet 15 to a compressed air storage tank (not shown) 100 from which the air may be conducted to and used at such points as may be found necessary in the complete and efficient operation of the engine as a whole. One or more check valves 14 may be employed to admit 105 air to a compressed air chamber 16 in the cylinder head 6. 17 designates threaded plugs to give access to the check valves 14.

The piston has no work to do on the down stroke, and hence in the absence of com- 110

pressed air above it, it will gravitate to its lower position.

The multiple cylinder head or annular support 4 is formed with an internal flange 5 upon which is supported and to which is secured by fastening means 19 a disk shaped stator body 20. Rising from the stator 20 are two or more series of vanes 21 and 22, said vanes being therefore stationary. Arranged above the stator 20 is a rotor 23 having on the under side thereof a plurality of series of vanes 24 and 25. The rotor 23 is mounted upon a vertical rotor shaft 26 stepped at its lower end in a bearing 27 and journaled between the upper and lower ends thereof in a bearing 28 attached to a stationary cover plate 29 which is connected at its margin to the heads of the cylinders 5. The shaft 26 extends above the cover plate 29 where it has associated therewith governor mechanism hereinafter more particularly described. 30 designates the central exhaust chamber of the turbine section of the engine which exhaust chamber is in communication with an exhaust pipe or connection 31 leading to the atmosphere. Leading from each of the cylinders 5 to the turbine portion of the engine is a plurality of obliquely disposed ports or passages 32. It will be observed in Fig. 2 that the passages 33 are arranged all the way around the turbine part of the engine so that a multiplicity of streams of expanding mixture are directed against the vanes of the rotor and stator until the fluid when about fully expanded enters the central exhaust chamber 30. It will be observed in Fig. 5 that the ports 32 are vertically elongated and are arranged to be uncovered by the respective piston 9 as it moves upwardly when an explosion occurs in the combustion chamber 18. The piston is provided with the usual packing rings 33 for the usual purpose.

In conjunction with each cylinder 5, I employ a cylindrical valve casing 34 containing a hollow piston valve 35 equipped on its peripheral face with packing rings 36 which are arranged at opposite sides of the outlet passage or port 37 of the casing 34, which port or passage 37 communicates with the combustion chamber 10 of the adjacent cylinder. The valve 35 has fixedly secured thereto an operating stem 38 which works through a stuffing box 39 in the upper head 40 of the casing 34. At the lower extremity of the stem 38 and within the valve 35, there is a pump plunger head 41 which is movable back and forth in a fuel feed pipe 42, the adjacent portion of said pipe forming a pump barrel so that in each upward movement of the valve 38, a working stroke of the plunger head 41 is effected thereby pumping a predetermined amount of fuel into the valve 35 and the valve casing 34. The lower head or end wall 43 of the valve

casing 34 embodies a stationary cone member 44 which is in effect an air valve. The valve body 35 is formed at the bottom thereof with a cone-shaped valve seat 45, which conforms to the shape of the member or valve 44, excluding air when the valve is in its lowermost position but admitting air to said valve and valve casing when the valve is elevated by the means hereinafter described. The port 37 above referred to communicates with a channel 46 extending around the valve casing 34 and the body of the valve 35 is formed with an annular series of outlet ports 37 which, when brought on a level with the channel 46, serve to release the explosive mixture which then passes through the port 47 into the combustion chamber 10 of the adjacent cylinder 5. The channel 46 is intersected by a compressed air pipe 48 which communicates at its receiving end with a port 49 in the adjacent cylinder 5 immediately adjacent to the head 6 thereof. An automatic check valve 50, shown as of the ball type is incorporated in the pipe 28 to prevent back pressure. The air compressed in the chamber 11 is forced through the pipe 48 past the check valve 50 into the annular channel 46, around the valve body 35 when the latter has been lowered and through the passage 37 into the combustion chamber 10 to scavenge the burned gases therefrom after each explosion. Preferably the valve casing 34 is provided near the bottom thereof with an annular air conduit or channel 51 to which air under pressure is fed from a suitable compressed air tank hereinabove referred to as supplied from the compressed air chamber 11.

Arranged above the cover plate 29 is a rotary support or plate 53 having a marginal annular upstanding flange 54 which is formed with diametrically opposite slots 55 through which are slidable governor controlled tappets 56 having rounded or arcuate working faces 57. Pivottally connected to the tappets 56 are links 58 the inner ends of which are pivotally connected to bell crank levers 59 pivotally supported by posts 60 rising from the support 53. The inner ends of the levers 59 are provided with cams or shoes 61 which coöperate with rollers 62 on the free extremities of a pair of arms 63 connected by pivots 64 to the posts 60 and arranged at opposite sides of the rotor shaft 26 as indicated in Figs. 3 and 4. Each of the arms 63 is provided at a point between the ends thereof with a roller 65 which works in an annular groove 66 adjacent to the lower end of a vertically movable governor operated sleeve or tubular weight 67 which embraces the upper end portion of the shaft 26. Each of the arms 63 is of telescopic formation, one section being tubular so as to receive the other section which carries the roller 62, the section which car-

ries the roller 62 being yieldingly sustained by means of a compression spring 68 housed within the tubular section of said arm. This prevents any cramping or binding action on the arms 62 as they cooperate with the shoes 61 of the levers 59. Extending in opposite directions from the shaft 26 and having a fixed relation thereto are arms 69 to which are pivotally connected centrifugally operated governor weights 70. Each of said weights comprises an inwardly extending finger 71 which engages the sleeve or weight 67 in such manner that when the weights 70 move outwardly away from the shaft 26, an elevating effect is obtained on the sleeve 67. The sleeve 67 is connected at its upper extremity by a ball and socket joint 72 with a spring tensioned lever 73 fulcrumed on a post 74 rising from a stationary part of the engine. Connected to the outer extremity of the lever 73 is a rod or stem 75 which is slideable through a fixed guide 76 and is yieldingly pressed in an upward direction by a compression spring 77 interposed between the guide 76 and a shoulder on the stem 75. The tension of the spring 77 is exerted to yieldingly hold the sleeve or weight 67 in a lowered position, the weights 70, in moving outwardly, serving to overcome the resistance offered by the spring 77.

The tappets 57, when projected outwardly by the action of the governor mechanism, come in contact with a roller 79 on the adjacent end of a push rod 80, one of said push rods being used in conjunction with each cylinder 5 and extending about diametrically across the head thereof as shown in Fig. 6. Each push rod 80 is formed with a V-shaped recess 81 at a point between the ends thereof and is provided with another V-shaped recess 82 adjacent to the extremity thereof. The recess 80 receives a gravity latch 83 having a pivotal connection at 84 with the arm 85 of one of a pair of locking dogs 86 employed for the purpose of locking the respective piston or check rod 8 so as to prevent movement of the piston 9 in the cylinder 5. The dogs 86 are formed with inwardly extending lips 87 which engage the extremity of the adjacent rod 8 as shown, and are mounted on oppositely located pivots 88 and geared together for simultaneous movement in opposite directions by sector gear faces or extensions 89. As the push rod 80 is thrust inwardly by the action of one of the tappets 57 against the roller 79 thereof, the shoulder formed by the recess 81 acts on the gravity latch 83 and thereby rocks the locking dogs so as to move the lips 87 thereof out of the path of the rod 8 to permit the piston 9 to move upwardly in the cylinder 5. As the movement of the push rod 88 continues, the gravity latch 83 rides upwardly on the inclined face 90 of an elevating block 91 adjustably secured to the cylinder head 6

thereby moving the gravity latch out of engagement with the recess 81 and permitting the push rod 80 to move further without engaging said latch. One of the locking dogs 86 has a contact arm 92 extending therefrom and forming a terminal of an ignition circuit. As the respective dog 86 swings in a direction to release the rod 8, the contact arm 92 makes contact with another stationary contact 93 forming the other terminal of the ignition circuit. This produces a spark at the plug 12 just after the rod 8 has been unlocked by the dogs 86. An explosion then takes place in the combustion chamber 10 with the result above described.

The other recess 82 of the push rod 80 engages one arm of an elbow lever 94 pivotally supported by a bracket 95 rising from the cylinder head 6 and having pivotally connected thereto the stem 38 of the valve 35 hereinabove described. In this way, the valve 35 is elevated to its charging position and the charge passes through the passage 37 into the combustion chamber 10. Immediately thereafter the valve 34 is released by the action of a normally stationary but adjustable block 96 having an inclined face 97 and otherwise corresponding in shape and function with the block 91 previously referred to.

The means for imparting rotary motion to the support or plate 53, comprises a shaft 98 journaled in bearings carried by the support 53, said shaft 98 having fast thereon a pinion 99 which meshes with an annular rack face 100 on the cover plate 29 hereinabove described. The shaft 98 also has fast thereon a gear 101 which meshes with another gear 102 on the rotor shaft 26, the last named gears preferably being of the spiral-type and the actuating gearing of the rotary support 53 being so designed as to impart a comparatively very low speed to the support 53, the speed being however sufficient to insure the outward movement of the tappets 57 under the centrifugal action of the governor mechanism hereinabove described. 103 designates a transmission or power delivering shaft which is geared to the rotor shaft 26 by the gears 104 and 105 115 shown as of the worm type.

From the foregoing description taken in connection with the accompanying drawings it will now be understood that the explosions take place in the combustion chambers of the cylinders 5 which are arranged in a circle around the turbine section of the engine. As the explosions take place, the expanding mixture is directed through the passages 32 against the vanes of the turbine and in this way rotary motion is imparted to the latter and to the rotor shaft 26. Two explosions occur simultaneously by reason of the action of the diametrically opposite tappets 57 on the push rods 80. As 130

additional load is imposed on the engine and as more power is required to maintain the speed of the engine at a certain number of revolutions per minute, explosions take 5 place in additional cylinders 5 by the coöperation of the tappets 57 with the push rods 80 of such cylinders, it being understood that as the speed of the rotor shaft decreases, the tappets 57 are thrust outwardly 10 to obtain the additional impulses or explosions for the purpose of causing the said rotor shaft to pick up its speed until the predetermined speed is obtained. It will also be observed that the entire operation of 15 the engine is automatic after the tripping blocks 91 and 96 have been properly adjusted so as to produce the operation of the locking dogs 86 and the lifting connections for the valves 35 at the proper periods.

20 The pumping action hereinbefore alluded to will be understood from the following:—

To start the motor a rod 80 is pushed across the head of the cylinder. Said rod will lift the valve allowing a charge of air 25 supplied under a pressure of 100 pounds from a tank provided for the purpose to mix with the gasoline lifted by means of the pump in the valve body. When the rod 80 and the notch 82, have performed that duty 30 the lift will come upon the adjustable block fixed to the cylinder head and will release the valve and allow it to close.

When this position has been reached the cock-dogs that hold the piston rod down 35 will be ready to let go of the upper end of the rod. This is accomplished by the notch provided on the rod 80 for that purpose, as there is a mixture of about 100 pounds pressure in the explosion chamber of the 40 cylinder. The piston will start up and at the same time the small rod that is fastened to the dog will make an electric contact and a spark will be created at the spark plug where the explosion will take place, with 45 the piston moving up. The piston will be driven up with about 500 pounds pressure. To offset this an air cushion is formed at the top of the piston and under the top cylinder head. As the explosion is about five 50 times as great as the compression and the compression is 100 pounds, it will readily be seen that there will be more air pumped than the engine will use.

As all the air cannot be discharged from 55 the cylinder the air that is trapped is about 300 pounds and will expand and as the ports are open under the piston it will be seen that the piston will be started down after the expansion is spent. To stop the piston at the 60 bottom a space is left for an air cushion to keep the piston from striking the bottom. When the piston has reached this position the dogs will close and catch it.

As each cylinder is operated independ- 65 ently of the other each cylinder will stand

idle until the governor comes in to a slow speed position when the rods 80 will be pushed across the cylinder head. Then the cylinders will start firing. The cylinders will start to fire in pairs across from each other. It is to be understood that there is no compression under the piston.

I do not desire to be limited to the details of construction hereinabove described as it will be apparent that the invention is susceptible of many changes in the form, proportion and minor details thereof which may properly fall within the scope of the appended claims.

1 claim:—

1. In a rotary internal combustion engine, the combination of a stator, a rotor coöperating therewith, turbine vanes on said rotor and stator, an annular series of stationary combustion chambers surrounding said turbine and having obliquely disposed outlets by means of which the expanding mixture is directed against said vanes, a normally locked piston in each of said cylinders, and means for unlocking the pistons as the speed 85 of the turbine decreases.

2. In a rotary internal combustion engine, the combination of a stator, a rotor coöperating therewith, turbine vanes on said rotor and stator, an annular series of stationary 95 combustion chambers surrounding said turbine and having obliquely disposed outlets by means of which the expanding mixture is directed against said vanes, a normally locked piston in each of said cylinders, and means for locking and unlocking said pistons controlled by the speed of the turbine.

3. In a rotary internal combustion engine, the combination of a stator, a rotor coöperating therewith, turbine vanes on said rotor 105 and stator, an annular series of stationary combustion chambers surrounding said turbine and having obliquely disposed outlets by means of which the expanding mixture is directed against said vanes, a normally 110 locked piston in each of said cylinders, means for locking and unlocking said pistons controlled by the speed of the turbine, the last named means comprising a rod extending from each piston, locking dogs co- 115 operating with said rods, and governor controlled means for shifting said dogs into and out of locking engagement with the respective piston rods.

4. In a rotary internal combustion engine, 120 the combination of a stator, a rotor coöperating therewith, turbine vanes on said rotor and stator, an annular series of stationary combustion chambers surrounding said turbine and having obliquely disposed outlets 125 by means of which the expanding mixture is directed against said vanes, an intake valve for each cylinder, governor controlled means for opening said valves at a predetermined speed of the engine, and an igni- 130

tion circuit also controlled by said governor mechanism, the ignition circuit being closed immediately before the opening of said intake valve.

5. In a rotary internal combustion engine, the combination of a stator, a rotor coöperating therewith, turbine vanes on said rotor and stator, an annular series of stationary combustion chambers surrounding said turbine and having obliquely disposed outlets by means of which the expanding mixture is directed against said vanes, an air and fuel intake valve for each cylinder, comprising 10 a tubular valve casing, a hollow cylindrical reciprocatory valve movable therein and provided with a plurality of outlet ports in the side wall thereof adapted to register with a passage leading to the combustion chamber of the cylinder, means controlled by the speed of the engine for opening said valve, said valve comprising a conical valve seat, a stationary valve having a fixed relation to the valve casing, a compressed air 15 conduit in communication with the space between said valve and valve seat, a fuel injecting plunger operating in a central bore in said stationary valve, and a fuel feed pipe leading to said bore.

20 6. In a rotary internal combustion engine, the combination of a stator, a rotor coöperating therewith, turbine vanes on said rotor

and stator, an annular series of stationary 25 combustion chambers surrounding said turbine and having obliquely disposed outlets by means of which the expanding mixture is directed against said vanes, an air and fuel intake valve for each cylinder, comprising 30 a tubular valve casing, a hollow cylindrical reciprocatory valve movable therein and provided with a plurality of outlet ports in the side wall thereof adapted to register with a passage leading to the combustion 35 chamber of the cylinder, means controlled by the speed of the engine for opening said valve, said valve comprising a conical valve seat, a stationary valve having a fixed relation to the valve casing, a compressed air 40 conduit in communication with the space between said valve and valve seat, a fuel injecting plunger operating in a central bore in said stationary valve, and a fuel feed pipe leading to said bore.

45 In testimony whereof I affix my signature.

WILLIAM J. DODGE.
